DESIGN FOR A GAME BOARD

Henry M. Bartle, Santa Rosa, Calif.

Application May 27, 1941, Serial No. 101,187

Term of patent 7 years

To all whom it may concern:

Be it known that I, Henry M. Bartle, a citizen of the United States of America, residing at Santa Rosa, county of Sonoma, State of California, have invented a new, original, and ornamental Design for a Game Board, of which the following is a specification, reference being had to the accompanying drawing, forming a part thereof wherein:

Sections of the circular feature of the design in Fig. 1 are lined for contrasting colors.

I claim:

The ornamental design for a game board, as shown and described.

HENRY M. BARTLE.
